Primary Examiner — Mitchell Siegel*(74) Attorney, Agent, or Firm* — Cardinal Law Group**(57) CLAIM**

The ornamental design for an inflatable trapezoidal play structure, as shown and described.

DESCRIPTION

FIG. 1 is a perspective view of an inflatable trapezoidal play structure;

FIG. 2 is a left side view of the of the inflatable trapezoidal play structure, the right side view (omitted) being a mirror image thereof;

FIG. 3 is a front view of the inflatable trapezoidal play structure;

FIG. 4 is a rear view of the inflatable trapezoidal play structure;

FIG. 5 is a bottom view of the inflatable trapezoidal play structure;

FIG. 6 is a top view of the inflatable trapezoidal play structure; and,

FIG. 7 is a perspective view of the inflatable trapezoidal play structure employed in an inflatable play structure system. The broken line showing of is included for the purpose of illustrating and forms no part of the claimed design.
